UNITED STATES PATENT OFFICE.

JOHN C. R. McCRUDDEN, OF HURSTVILLE, NEAR SYDNEY, NEW SOUTH WALES,
AUSTRALIA.

MACHINE GUN.

Application filed June 19, 1920. Serial No. 390,153.

To all whom it may concern:

Be it known that I, JOHN CHARLES REGINALD McCRUDDEN, subject of the King of Great Britain and Ireland, residing at 5 "Fleurbaix," Haig Street, Hurstville, near Sydney, New South Wales, Australia, have invented certain new and useful Improvements in Machine Guns, of which the following is a specification.

10 This invention relates to machine guns of the automatic recoil type, having an axially moving breech block with key locking means.

The machine gun in which this invention consists is sufficiently low in weight to permit it to be used as a shoulder arm in emergencies and to be moved and handled by one man under all service conditions. The novel features and detail of structure hereinafter particularly described have been devised in 20 inter alia with a view to economising time and labour in recharging the gun with ammunition; to making the gun capable of sustained operation in long bursts of fire; to providing efficient and readily controlled means for 25 regulating the rate of fire and varying that rate whilst the gun is in operation; to carrying away heat from the chamber and barrel at a rate which will enable the gun to be used with safety in prolonged bursts of fire; 30 to adequately protecting the gun parts against fouling or injury by sand, mud or dust, and facilitating cleaning of the parts; to providing a rugged design of parts without elements of delicate proportions which 35

would be liable to suffer injury in prolonged or rough use; to rendering of the weapon convertible without structural change of parts for use optionally as a single fire shoulder arm, or as an automatic repeater arm 40 fixed or laid in an appropriate support; to augmenting the capacity of the gun for use under exceptional conditions where long bursts of fire are called for, by providing readily detachable and replaceable magazines of large capacity which contain a very 45 large number of cartridges; to providing means for effectively smothering the explosion flash and muffling the explosion report, thereby to make the gun more useful for 50 the reason that it will not disclose its position to an enemy readily, either in daylight or night service, its operators thus better eluding detection by opposing forces, to providing a design, which is structurally adapted 55 for the fitting to it of water cooling means

to replace its standard air cooling means for restraining the temperature in the barrel within a safe working limit; to permitting ready removal and replacement of all un-fixed elements without recourse to workshop 60 tools, thus facilitating the dismantling of the gun and its ready re-assembling, and otherwise generally to providing a military service weapon having all-round utility for rough field and trench work and for air-plane and anti-airplane fighting and for 65 naval purposes.

In the accompanying drawings, Fig. 1 is a side elevational view of a gun according to the present invention complete, as it appears with the sighting leaf raised, and the magazine set in the throat in the breech, the magazine being of a new type adapted for carrying 60 or more small arm service cartridges of .303 or like standard dimension. 75

Fig. 2 is a sectional elevation of the central portion of the gun on an enlarged scale, displaying the parts in cocked position ready for firing, with a cartridge in the barrel chamber, and the bolt locked; 80

Fig. 3 is a horizontal plan on the section line 3—3 Fig. 2;

Fig. 4 is a longitudinal sectional elevation showing the gun parts in the position they occupy during the recoil, the barrel and the 85 breech carriage being fully recoiled, and the bolt unlocked and commencing its recoil movement in the carriage;

Fig. 5 is a similar sectional elevation showing the position of the gun parts when the bolt is fully recoiled, the barrel and breech carriage restored to normal position in the body casing, and the bolt about to begin its closing movement in which it is brought up to the barrel chamber, and in 90 moving forward takes with it a fresh cartridge from the top of the magazine; in this figure the recoiling parts are shown in full lines, whilst the steady parts of the gun are indicated in dotted lines; 95

Fig. 6 is a perspective view of the breech carriage shown attached to the barrel breech; 100

Fig. 7 is a perspective view of the bolt latch; 105

Fig. 8 is a perspective view of the bolt;

Fig. 8^a is a perspective view of the trace head on the bolt restoring spring;

Fig. 9 is a sectional elevational view showing the lock assembly with the gun parts in 110

the same position as in Fig. 2, that is, ready for firing; the trigger safety catch is shown set;

Fig. 10 is a similar view showing only the lock assembly as the parts appear at the moment the firing pin has advanced and struck the cartridge primer, but before recoil has commenced;

Fig. 11 is a fragmentary view showing some of the lock parts as the same appear when the firing pin has been reset during the recoil movement; the trigger in this case, as well as in Fig. 10 being shown pulled;

Fig. 12 is a transverse sectional view on the plane 12—12 Fig. 9;

Fig. 13 is a transverse sectional view on the plane 13—13 Fig. 9;

Fig. 14 is a fragmentary perspective view of the hand grip and the trigger assembly;

Fig. 15 is a perspective view of the breech body casing, the rear end of which is fixed to the butt head;

Fig. 16 is a fragmentary side elevational view explanatory of the casing latch by which the body casing is fixed to the butt head;

Fig. 17 is a fragmentary rear elevational view corresponding with Fig. 16;

Fig. 18 is a longitudinal sectional view through the forward end of the barrel and the radiator, showing the flash trap and report muffler;

Fig. 19 is a transverse sectional view on a plane 19—19 Fig. 18;

Fig. 20 is a transverse sectional view through the barrel, the radiator, and the radiator casing, at an intermediate position in the length of the barrel, as, for instance, on a plane 20—20 Fig. 18;

Fig. 21 is a longitudinal sectional view showing the mounting of the magazine and the cartridge feed mechanism therein;

Fig. 22 is a transverse section on an enlarged scale on the plane 22—22 Fig. 1.

All the drawings are made to uniform scale, except Figs. 1 and 21 and the perspective views, which latter are approximately to scale.

The gun as illustrated is fitted with an air cooled radiator, but in practice this radiator may be removed and a water jacket fitted directly on the barrel to completely enclose the barrel from a point near the muzzle to a point a little rearward of the chamber enlargement, thereby including the forward end of the chamber. The water jacket would be fitted with gland ends through which the barrel would work whilst the water jacket would be held steady.

The main structural features will be best understood by reference to Figs. 3, 6, 7, and 8. The breech end of the barrel is fixed in the forward end of a breech carriage in which an axially moving bolt is accommodated, and said bolt is engaged

through a master pin by a bayonet slot key or "latch" to lock it in the breech carriage, the whole structure being adapted to recoil as one member, thereby compressing a restoring spring which functions to cant the latch to locked position whilst assisting to effect reversal of the recoil movement; the bolt is closed by an independent resetting spring which is tensioned during the recoil action.

The breech carriage 30, which is best seen in Fig. 6, consists of two lateral cheeks slotted on one side as shown at 31—32 for purposes hereinafter explained, offset at 33 midway of their length to give clearance for the latch, and having bearing eyes 34 in its rear ends to carry a wrist pin 35 on which the latch 36 (Fig. 7) is mounted. The wrist pin 35 passes through the latch eyes 37, and is fixed in position by a wedge key 38 driven down behind a flat 39 on the middle length of the pin, said wedge key 38 serving also to hold a spring 40 which is provided to buffer the bolt at the back end of its opening movement. 41 (Fig. 8) is the bolt. It is a slide fit between the forward cheeks of the carriage 30; a lug 42 on the right side of its forward end works as a slipper in the slot 31 which forms a guide for it. A hole 43 in the rear end of the bolt 41 accommodates a withdrawable master pin 44 which is held fixed by a bayonet catch 45 (see Fig. 3.) When this master pin is removed, the gun cannot be operated as it forms the abutment of the bolt; it also serves for manually retiring the carriage and parts associated with it to set the gun for the first shot. After firing the first shot the action is automatic so long as a charged magazine is in position, and so long as the trigger is held pressed. The master pin 44 is a free running fit in the carriage guide slot 32. It is also a free running fit for the L-shaped notched slots 46—47 in the wing portions of the latch 36. The notches 47 of the slots 46 form abutment seatings for the master pin 44, so that when the latch 36 is set downward, as in Fig. 2, the bolt 41 is positively locked in the carriage 30, with its forward end closing the breech of the barrel chamber 48. A cupped lug 49 on the top side of the rear end of the latch 36 forms an abutment for a ball-headed plunger 50, against which acts the helical restoring spring 51. The rear end of this spring is housed in a tension adjusting screw cap 52. The lug 53 on the top side rear end of the bolt 41 is mounted to carry the trace head 54 of the bolt resetting spring 55; this is a helical spring in tension, having its forward end carried on a hook bolt 56, the tension being adjustable by turning a knurled nut 57 which runs on the stem of the hook 56. 58 are ramp faces carried on a shoe 59, the fore-and-aft position of which is ad-

justable by means of a knurled nut 61 accommodated in a gap in the butt head 60.

The striker faces 62 on the wings of the latch 36, contact with the shoe ramps 58 during the recoil movement of the breech carriage 30, and the position of the shoe 59 therefore determines the time in the recoil movement at which the latch releases the bolt to allow it to move backward in the breech carriage. 63 is an extractor spring hook, which, as usual, is mounted on a pin 64 on the side of the bolt 41, with its hooked head 65 positioned to locate in a clearance space 66 in the breech of the chamber, to engage the base rim 67 on the cartridge case 68. 69 is an ejector in the rear side of the carriage 30; a slot 71 in the off side of the bolt offers clearance for the bolt movement past this ejector.

20 The whole of the mechanism between the butt and the radiator casing is contained in the body casing 72 (see Fig. 15). This casing is laterally slotted on the near side at 73 to permit of the ejecting of the empty shell, at 74 to provide clearance for movement of the master pin 44 with the bolt, and at 75 on both sides, to straddle the ends of the latch wrist pin 35.

25 The hand grip and trigger assembly (Fig. 14) is an independent unit, and is set up in the lower part of the body casing 72 in the manner which will be best understood on reference to Fig. 2. The structural features of this assembly will be described later. 30 Its mounting means consist in a hooked claw 77, engageable over a bridge pin 78 in the body casing 72, the rebated side edges 79 fitting into a rebate in the bottom of the casing 72 (see Fig. 12), the assembly being 35 locked in position by the engagement of the overhanging nibs 80 under the heel piece 81 of the butt head 60 (Fig. 10). The rear part of the bottom of the casing 72 is slotted as shown at 82 (Fig. 15), and is longitudinally grooved as shown at 83 at either side to engage spigot ribs 84 on the sides of the butt head 60 (Fig. 13).

40 Upon the barrel 29 a sleeve 85 (preferably constructed of aluminium) is slipped on, this sleeve carrying helically disposed thin radiator fins 86 between which and the casing 91 a little clearance is left. The radiator assembly is locked on the barrel between the abutment formed by the forward end 87 of the carriage 30 and the clamping nut 88 which is screwed on to the barrel muzzle (Fig. 18.) The nut 88 is formed with two or more wings 89 which set in slide guides 90 fixed in the radiator casing 91. 45 The forward end of the barrel is maintained in axial alignment with the casing 91 by these wing pieces. Rearwardly the barrel and breech parts are supported on wing pieces 92 which run in slide guides 93 formed 50 in the forward part of the body casing 72.

The butt end of the radiator casing 91 is made slightly conical to fit tightly on the slightly tapered forward end 95 of the body casing 72, and is clamped thereon by a screw tightened band 94 so that said radiator casing 91 and said body casing 72 together form a complete enclosure for the gun parts, in which enclosure the barrel, the radiator mounted on the barrel, the breech carriage, and the parts contained in the breech carriage are movable axially. 55

Forward of the slide guides 90 in the radiator casing 91 the flash trap and report muffler device is contained. The casing 91 extends beyond the gun muzzle a few inches, and the nut 88 forms a bell mouth 129 for the muzzle. The forward end of the casing 91 is flanged inwardly as shown at 130, leaving a central mouth 131 of considerably greater diameter than the barrel bore. Intermediate the muzzle bell 129 and the casing mouth 131, an open end cone 132 is mounted, with its rear narrow end slightly forward of the bell 129. This cone is centred and carried at its rear end by means of a spider frame 133, which is a push fit in the casing 91; around its forward end it is fixed in the casing 91 by rivets 134 or otherwise, so as to leave an annular space between it and the casing. The wide end of the cone is incurved slightly to form a circular lip 135. A clearance space 137 is allowed between the rear end of the cone 132 and the mouth of the bell 129; this clearance space is shorter than a bullet length in order that a bullet in passing into the cone 132 will substantially block its narrow mouth and cause the following gases to divert into the annular space surrounding the cone, where they expand, and in passing forward to find exit through the annular lip space at 135 induce a following draft of cold air through the apertures in the body casing and over the radiator. In passing through the annular space the flash is extinguished. 100

105 On reference to Fig. 22 it will be noted that the inward flutings 138 in the forward extension of the body casing 72 are located in alignment with the outward flutings 139 in the butt end of the radiator casing 91, the 110 passages formed by these flutes being open at the rear end (see 140, Fig. 1). These 115 passages 141 admit a current of air forwardly into the radiator space in the casing 91, air draft being established in the manner 120 hereinafter described.

125 In the assembling of the gun parts, the bolt 41 and the latch 36 are set up in the breech carriage 30, said carriage being attached at its forward end to the screwed butt of the barrel, the radiator being fixed on the barrel.

130 This assembly is inserted from the rear into its slide mountings in the body casing and radiator casing, which have been first

clamped together by the band 94 and the master pin is inserted through the slots 74—32—46 and through the hole 43 in the bolt. Then the spring 55 is connected to the hook 56 and the lug 53. The trigger assembly (Fig. 14) is then introduced by taking the hook lug 77 over the bridge pin 78 and swinging up the back end of the assembly. The rear end of the body casing 10 is now slid into its seat in the butt head 60, and the housing latch 96 is swung downward from the open position shown in Fig. 16 to the closed position shown in Fig. 9, and the pinching screw 97 screwed home. The stock 15 is thus engaged to the body casing quite firmly, and the trigger assembly is locked in its position by the engagement of the nibs 80 under the heel piece 81 of the butt head 60. This locking in of the trigger assembly 20 is best seen in Fig. 10. The operative parts of the gun can be removed very rapidly by dismounting the magazine, releasing the housing latch 96 after backing off the milled head screw 97, drawing the butthead backward, dropping down the trigger assembly, 25 withdrawing the master pin, releasing the trace head 54 from the bolt lug 53, and drawing the barrel and breach carriage assembly out of the casings.

30 The trigger assembly comprises a hollow hand grip 98 in a slot in the rear part of which is mounted a safety latch 99 against which a spring 100 bears to bring it normally to the outer position shown in Fig. 9.

35 When in this position the offset pin 101 on its top end working in the slot 102 in the notch bolt 103 moves said bolt forwardly so that its head 104 enters the path of the stop tooth 105 on the rear of the trigger 106. The trigger is mounted on a pin 107 carried above the top of the trigger guard 108. The knuckle 109 on the shoulder of the trigger co-acts with the sear tappet 110. This tappet is mounted at its 40 rear end on a pivot pin 111 and is normally pressed downward towards the trigger knuckle by a spring 112. When the trigger is in the safety position, the tappet 110 is held in low position by the spring 112 and in that low position it cannot engage the striker tail 113 of the sear 114. A spring 115 functions to hold the sear 114 downward against a stop pin 116. The sear tooth is engageable with a notch 117 in the tumbler 55 118. The tumbler is provided with a toothed sector edge 119, and on the opposite side of its mounting pin 120 with a tappet tail 121. The tumbler and the sear and the sear spring are mounted in a slotted cavity in the back 60 end of the bolt with their tails protruding downward through the bottom of said slot, 122 is a cocking pawl capable of a little rocking movement limited by the shape of its seating in the nose portion of the trigger assembly frame. The cocking pawl is in

alignment with the tappet tail 121 of the tumbler 118. The sector edge 119 of the tumbler meshes with a toothed rack 123 on the rear end of the striker 124. The striker is as usual terminated at its forward end to a hardened conical point 125 arranged to contact with the cartridge primer. Rearward of the conical point 125 a collar 126 fixed on it forms an abutment for the striker spring 127. The striker assembly is mounted in a tubular pocket 128 in the bolt. In the operative position of the trigger shown in Fig. 10, the sear tappet 110 is lifted by contact therewith of the trigger knuckle 109, so that said tappet being thus raised against the pressure of the spring 112 is brought into the horizontal path traversed by the sear 114 during the recoil action of the gun parts. The trigger 106 cannot, however, be pulled except when the hand stock 98 is embraced so that the safety latch 99 is forced inward by pressure of the palm of the hand. The access hatch 142 in the top side of the body casing 72 is closed by a slip-in cover plate 143, which at its forward end is formed with a nib 144 which takes under a lip 145 in the forward part of the casing. Along its sides the cover plate 143 sets into a rebate 146, and it is locked in position by a hit-and-miss latch 147, which is engageable below the rebate edges 146. 148 is a knurled nut, which carries the latch 147.

The magazine 149 is a segmental box identical in transverse section (see Fig. 22) with standard service type magazine for shoulder arms. It is inserted at its delivery end 150 up into the feed throat 153 in the breech carriage. Its upper position is determined by its fitting into the pocket in said throat as in the case of an ordinary service rifle, and it is latched in position by a spring latch 151, which engages a hook staple 152 behind the throat 153. The weight of the magazine 149 and its contents is sustained by carrier arms 154—155, which are supported on a 110 stud hanger 156, said stud hanger being adapted to slide on a fixed carrier pin 157. This pin projects forwardly from a collar 160, which is fixed on the butt collar 161 of the radiator, which is a tight fit on the 115 "Knox form" exterior of the barrel chamber 48, that is, on the enlarged rear end of the barrel.

In this magazine, taper-shaped cartridges are packed so that they set in staggered order (the magazine width being greater than the diameter of one cartridge, but less than twice a cartridge diameter), the cartridge at the mouth of the magazine being lightly held by the inturned lips 167 on the 125 cheeks of the magazine (see Fig. 5), but so that when the bolt 41 is moved forwardly, its fore end takes behind the base rim of the cartridge and slides it endwise out of the magazine into the barrel chamber; as each 130

cartridge in turn is thus slid out of the magazine, the next cartridge in order is held in position in the magazine mouth for delivery into the barrel chamber in the next forward movement of the bolt.

The pivot pin 162 supported by the stud hanger 156 carries the feed arm 158, which extends through a slot 165 and acting through the back spring 159 in the magazine supports 10 and moves the platform 163 therein. The arm 158 is swung forwardly by a coiled wire spring 164 and functions through the platform to urge the cartridges in the magazine forward towards its mouth, whence they are 15 taken one by one by the bolt action and delivered into the barrel chamber. This system of construction of the magazine and its mounting offers a positive advantage for reloading rapidly in action without disturbing 20 the lay of the gun, as the gunner, while still retaining the gun in position, may in a one-hand movement, release the latch 151, swing the magazine on the pin 162, and slide it forward, thus bringing the hanger 156 off the 25 pin 157. An empty magazine is thus detached by an instant dexterous movement, and by a reverse movement a full magazine inserted. Continuity of firing is therefore interrupted only for a period of a second or 30 two when a magazine is exhausted, and as each magazine contains a very large number of cartridges, the gun is thus qualified in a special degree for repeated prolonged bursts of firing, which very frequently is a 35 consideration of major importance.

The operation of the gun as an automatic gun is as follows:

A magazine being placed in position, and a cartridge inserted into the chamber by 40 once manually operating the locking mechanism by reciprocating the breech carriage by means of the master pin 44, the trigger 106 is pulled, whilst at the same time the safety latch 99 is inclosed by pressure of the 45 palm of the gunner's hand, thus withdrawing the check 103 and allowing the trigger to be moved. In the pulled position, the trigger bears the sear tappet 110 upward from the idle position shown in Fig. 9 to the 50 firing position shown in Figs. 10 and 11. The upward movement of the tappet 110 acting against the tail 113 of the sear 114, draws the tooth of the sear out of engagement with the notch 117 of the tumbler 118. 55 The striker spring 127 being thus liberated, drives the striker 124 forward, causing its firing point 125 to strike the cartridge primer and explode the cartridge. The bullet passes out of the barrel 29 through the 60 bell mouth 129 and thence through the cone 132. As it passes from the barrel muzzle into the narrow mouth of the cone 132 the fiery gases following it are diverted laterally and are splayed outwardly, and pass 65 through the apertures in the spider 133.

The high pressure gases thus diverted into the annular space surrounding the cone 132, induce an air draft through the fluted passages 141, and through the radiator forwardly. This draft, washing the helically 70 disposed radiator fins, abstracts heat from them. The flash is extinguished before it reaches the tube mouth 131. As the temperature of the barrel is practically uniform on all sides of it, bending and twisting of 75 the barrel under prolonged fire does not take place, and the accuracy of the gunner's aim is therefore not substantially disturbed. The reciprocating movement of the barrel and the radiator fins operates to procure 80 effective washing contact of the cooling air with the metal surfaces, thereby exalting the rate of transference of heat through the radiator to the air. In addition to the cooling air indrawn through the fluted passages 85 141, air is also drawn through the body casing and through the clearance space in the bottom part of it where the magazine support 157 is located. There is thus a 90 considerable transverse section through 95 which air may enter the radiator, so that a quite free flow of air is available for movement through the radiator. The cone 132 also functions to a limited extent as a sound muffler, so that the noise of the explosions of the gun is deadened, and it is difficult at a little distance to locate the position of the gun by the sound of the fire.

When the cartridge charge is exploded, recoil takes place and the barrel 29 and 100 breech carriage 30 and the assembly of parts supported therein, move bodily rearward (see Fig. 4). In the recoil movement from the position shown in Figs. 2, 3, and 9 to the position shown in Fig. 4, the restoring 105 spring 51 is compressed. When the strikers 62 on the latch 36 contact with the shoe ramps 58, the latch is lifted so that its long slot is brought up to alignment with the master pin 44 which is carried in the bolt. 110 Immediately the latch is so cleared, the back pressure of the gases in the barrel 29 acting through the empty shell operates to recoil the bolt 41, and simultaneously with this recoiling movement of the bolt, the 115 reaction on the barrel assembly assisted to a greater or less extent by the restoring spring 51, according to its tension adjustment, effects the bodily return of the barrel and breech carriage assembly forward. The 120 backward movement of the bolt continues according to the adjustment of the bolt resetting spring 55, the buffer spring 40 taking the impact of the bolt before the master pin strikes the back end of the latch slot 46. At 125 this point the bolt has moved back its full travel (Fig. 5), dragging the empty shell of the cartridge 68 back with it by means of the extractor hook 63. In this movement the spring hook 63 moves the cartridge 130

across the nose of the bolt, bringing the far edge of its flange into alignment with the ejector 69, upon contacting with which and clearing the back end of the barrel 5 chamber, the empty shell is ejected to the right, out through the clearance space 31 in the side of the breech carriage, and out through the opening 73 in the right side of the body casing 72. Forward return movement of the bolt now taking place rapidly, the barrel and breech carriage assembly having meantime moved forward to the normal advanced position, a new cartridge which has come up into the magazine mouth 10 as soon as the top of that mouth was cleared when the underside of the bolt passed back over it, comes into the path of the bolt, and the bolt, in advancing, drives said cartridge into the barrel chamber.

20 The entry of the straight portion into the notch portion of the latch slot 46 is curved for the purpose of imposing a downward pressure on the latch when the master pin contacts with it, to ensure that 25 the latch will close rapidly as soon as the master pin 44 reaches the notch position and thus to ensure that abutment will be established for the bolt instantly upon its attaining the firing position. This is very 30 important, as the sear is tripped just as the closed position of the bolt is attained, and the abutment for the bolt must be established by fully closing down the latch 36 on the master pin before the reaction of the 35 explosion is taken by the bolt.

The cocking of the trigger mechanism is effected automatically. In the recoil movement (about to begin as shown in Fig. 10), the tail 121 of the tumbler 118 strikes the 40 cocking pawl 122, and the tumbler is thus reversed from the position shown in Fig. 10, to the position shown in Fig. 11. Meantime, the tail of the sear 114 has passed the back clear of the sear tappet 110, and the 45 sear is restored by its spring 115, so that its tooth engages the notch 117 of the tumbler, thus holding the tumbler in cocked position. In this reversing movement of the tumbler, its toothed edge 119, meshing with the rack 123, retires the firing pin 124, thus 50 compressing the firing spring 127. In the next forward movement of the carriage, a new cartridge having been introduced into the chamber of the barrel as already described, 55 firing takes place automatically. The gun will continue to operate automatically in this manner so long as the trigger is held pulled and cartridges are available in the magazine. It may be operated as a single- 60 firer by pulling the trigger and releasing it rapidly before the bolt is restored to firing position after the recoil. The adjustments necessary to time the gun and to ensure effective movement of the several elements in 65 their proper relation are readily made

through accessible devices. Practically only three adjustments are necessary: Firstly, the tensioning of the bolt-resetting spring 55 by means of the milled nut 57; secondly, the tensioning of the restoring spring 51 by 70 means of the milled cap 52; and thirdly, the positioning of the shoe 59 by means of the milled nut 61. The rate of fire may be varied whilst the gun is in automatic operation by adjusting the nut 61, thereby to 75 move the shoe 59 forwardly or backwardly. There is necessarily a limited range of movement for the shoe 59. In its extreme permissible forward position, maximum 80 rapidity of fire is obtained, whilst in its extreme rearward position the gun is adjusted for automatic fire at the slowest rate for which it is structurally adapted.

What I claim as my invention and desire to secure by Letters Patent is:—

1. A machine gun having a recoilable barrel, a carriage attached to said barrel as a rearward extension thereof and axially slideable therewith, a body casing surrounding said carriage, an axially sliding bolt, a withdrawable master pin mounted in the rear end of said bolt and serving as an abutment therefor, a drop down latch for said bolt housed in said carriage said latch being automatically opened in the recoil movement 95 of the carriage and automatically closed in the forward return movement thereof, trigger mechanism mounted in the body casing, means for automatically cocking and firing the gun engageable by said trigger mechanism, and means for varying the rate of fire during action.

2. A machine gun having a recoilable barrel, a carriage attached to said barrel as a rearward extension thereof and axially slideable therewith, a body casing surrounding said carriage, an axially sliding bolt, a withdrawable master pin mounted in the rear end of said bolt and serving as an abutment therefor, a drop down latch pivotally 105 carried at its rear end in the rear end of said carriage, L-shaped slots in the sides of said latch adapted to receive said master pin, automatic means for lifting said latch to permit free backward movement of said bolt during the recoil motion of the carriage, and means for restoring said latch to locking position during the forward movement of the carriage consisting of a cupped lug 110 on the top side of the rear end of said latch and a ball-headed spring plunger abutting in said lug.

3. A machine gun having a recoilable barrel, a carriage attached to said barrel as a rearward extension thereof and axially slideable therewith, a body casing surrounding said carriage, an axially sliding bolt, a withdrawable master pin mounted in the rear end of said bolt, a pivoted drop down latch for said bolt housed in said carriage, slots in the 115

sides of said latch adapted to receive said master pin, a cam surface on the forward end of each of said slots, a cupped lug on the top side of the rear end of said latch, and 5 a ball-headed spring plunger abutting in said lug.

4. A machine gun having a recoilable barrel, a carriage attached to said barrel as a rearward extension thereof and axially slide- 10 able therewith, a body casing surrounding said carriage, an axially sliding bolt a with- drawable master pin mounted in the rear end of said bolt, a pivoted drop down latch for said bolt housed in said carriage, slots 15 in the sides of said latch adapted to receive said master pin, a cam surface on the for- ward end of each of said slots, strikers on the base of said latch, an adjustable ramped shoe in said body casing adapted to be en- 20 gaged by said strikers, and means for man- ually positioning said shoe.

5. In a machine gun in which the bolt slides axially in a breech carriage which is fixed to the barrel and recoils with it, a 25 spring operated firing pin housed in the bolt, a tumbler pivotally mounted in the bolt, a rack on the rear end of said pin meshing with a sector on said tumbler, a tappet tail on the tumbler engageable with a cocking 30 pawl in the trigger assembly, a tailed sear mounted in the bolt and engageable with the tumbler and a tappet movable by the trigger to trip said sear and thus release the tumbler and firing pin.

35 6. A machine gun having a recoilable barrel, a carriage attached to said barrel as a rearward extension thereof and axially slide- able therewith, a body casing surrounding said carriage, an axially sliding bolt, a with- 40 drawble master pin mounted in the rear end of said bolt, a pivoted drop down latch for said bolt housed in said carriage, slots 45 in the sides of said latch adapted to receive said master pin, a cam surface on the for- ward end of each of said slots, a cupped lug on the top side of the rear end of said latch, a ball-headed spring plunger abutting in said lug, a lug on the rear top side of said bolt, a bolt resetting spring adapted to engage 50 said lug, and means for adjusting the tension of said resetting spring and of said spring plunger, a releasable housing latch, and a releasable spring trace head.

90 7. A machine gun having a recoilable barrel, a carriage attached to said barrel as a rearward extension thereof and axially slide- able therewith, a body casing surrounding said carriage, an axially sliding bolt, a with- 95 drawble master pin mounted in the rear end of said bolt, a pivoted drop down latch for said bolt housed in said carriage, slots 100 in the sides of said latch adapted to receive said master pin, a cam surface on the for- ward end of each of said slots, spring means adapted to return the barrel and carriage, and independent spring means adapted to independently return said bolt.

105 8. A machine gun having a recoilable barrel, a carriage attached to said barrel as a rearward extension thereof and axially slide- able therewith, a body casing surrounding said carriage, an axially sliding bolt, a with- 110 drawble master pin mounted in the rear end of said bolt, a pivoted drop down latch for said bolt housed in said carriage, slots 115 in the sides of said latch adapted to receive said master pin, a cam surface on the for- ward end of each of said slots, a bridge pin mounted in said body casing, a trigger frame, a hook on said frame engageable with said bridge pin, projecting nibs and rebated side edges on the trigger frame, a rebate in the bottom of said body casing to engage said rebated side edges, a butt head, and a heel piece on said butt head adapted to be 60 65 70 75 80 85 90 95 100 105 110 115 engaged by said projecting nibs.

8. A machine gun having a recoilable barrel, a carriage attached to said barrel as a rearward extension thereof and axially slide- able therewith, a body casing surrounding said carriage, an axially sliding bolt, a with- drawable master pin mounted in the rear end of said bolt, a pivoted drop down latch for said bolt housed in said carriage, slots 60 in the sides of said latch adapted to receive said master pin, a cam surface on the for- ward end of each of said slots, a bridge pin mounted in said body casing, a trigger frame, a hook on said frame engageable with said bridge pin, projecting nibs and rebated side edges on the trigger frame, a rebate in the bottom of said body casing to engage said rebated side edges, a butt head, and a heel piece on said butt head adapted to be 65 70 75 80 85 90 95 100 105 110 115 engaged by said projecting nibs.

9. A machine gun having a recoilable barrel, a carriage attached to said barrel as a rearward extension thereof and axially slide- able therewith, a body casing surrounding said carriage, an axially sliding bolt, a with- drawable master pin mounted in the rear end of said bolt, a pivoted drop down latch for said bolt housed in said carriage, slots 90 in the sides of said latch adapted to receive said master pin, a cam surface on the for- ward end of each of said slots, a cupped lug on the top side of the rear end of said latch, a ball-headed spring plunger abutting in said lug, a lug on the rear top side of said bolt, a bolt resetting spring adapted to engage 95 said lug, means for adjusting the tension of said resetting spring and of said spring plunger, a releasable housing latch, and a releasable spring trace head.

10. In an automatic machine gun having a breech carriage attached to the rear end of the barrel, and an axially sliding bolt and a drop latch therefor housed in the breech carriage, a withdrawable master pin detach- ably carried in the bolt and forming engag- ing means between the bolt and the latch, said master pin being extended to protrude laterally through slide slots in the breech carriage and the body casing.

In testimony whereof I affix my signature. JOHN C. R. McCRUDDEN.
